UNITED STATES PATENT OFFICE

159,169

JAR

Frasier Smith, Wheeling, W. Va., assignor to
American Molasses Company, New York, N. Y.

Application April 1, 1949, Serial No. 1,747

Term of patent 14 years

(Cl. D58—25)

To all whom it may concern:

Be it known that I, Frasier Smith, a citizen of the United States, residing at Wheeling, in the county of Ohio and State of West Virginia, have invented a new, original, and ornamental Design for a Jar, of which the following is a specification, reference being had to the accompanying drawing, forming part thereof.

Figure 1 is a side elevational view of a jar showing my new design; and

Figure 2 is a horizontal sectional view taken on line 2—2 of Figure 1.

I claim:

The ornamental design for a jar, as shown.
FRASIER SMITH.
